UNITED STATES PATENT OFFICE

GOTTFRIED NIEBEL, OF NEW YORK, N. Y.

DESIGN FOR AN ELECTRIC BULB OR SIMILAR ARTICLE

Application filed December 5, 1929. Serial No. 33,657. Term of patent 14 years.

To all whom it may concern:

Be it known that I, GOTTFRIED NIEBEL, a citizen of the United States, and resident of 419 West 115th Street, in the city of New York, in the county of New York and State of New York, have invented a certain new, original, and ornamental Design for an Electric Bulb or Similar Article, of which the following is a specification, reference being had to the accompanying drawing, forming part thereof.

Figure 1 is an elevation of an electric bulb or similar article showing my new design and Figure 2 is a top plan view thereof.

I claim:

The ornamental design for an electric bulb or similar article substantially as shown.

Signed at New York, in the county of New York and State of New York this eighteenth day of November, A. D. 1929.

GOTTFRIED NIEBEL.
